UNITED STATES PATENT OFFICE.

JOHN M. FEDDERS, OF BUFFALO, NEW YORK, ASSIGNOR TO FEDDERS MANUFACTURING COMPANY, INC., OF BUFFALO, NEW YORK, A CORPORATION OF NEW YORK.

METAL-BENDING MACHINE.

1,278,897.

Specification of Letters Patent. Patented Sept. 17, 1918.

Application filed May 22, 1916. Serial No. 99,046.

To all whom it may concern:

Be it known that I, JOHN M. FEDDERS, a citizen of the United States, residing at Buffalo, in the county of Erie and State of New York, have invented new and useful Improvements in Metal-Bending Machines, of which the following is a specification.

This invention relates to a machine particularly designed for bending, folding and 10 seaming corrugated strips of metal to form units or sections of radiators used for the circulation of air and water in cooling internal combustion engines. A machine of this type is shown and described in Patent 15 No. 1,226,490 dated May 15, 1917.

The object of this invention is to provide a machine of this character which not only permits of bending, folding and seaming or locking the end walls of one unit of a radiator core made from one piece of sheet metal, but also makes provision for the insertion of the radiating webs or fins ordinarily used to provide a plurality of rows 20 of air conducting passages between the opposing side walls of each unit. These webs or fins are seamed or locked between the opposing side walls of each unit during the same operations in which the end walls thereof are formed.

30 A further object of this invention is to provide a machine which is simple, yet strong and durable in construction, efficient and positive in operation, and which can be manipulated with ease and quickness.

35 In the accompanying drawings: Figure 1 is a top plan view, partly broken away, of a bending machine embodying my invention. Fig. 2 is a vertical transverse section thereof taken on line 2-2, Fig. 1. Fig. 3 is a vertical longitudinal section on line 3-3, Fig. 1. Fig. 4 is a fragmentary vertical longitudinal section on line 4-4, Fig. 1. Figs. 5 and 6 are fragmentary vertical transverse sections taken on the correspondingly numbered lines of Fig. 1. Fig. 7 is a top plan view of the folding blade lever and associated parts. Fig. 8 is a fragmentary vertical transverse section, similar to Fig. 2, but showing a different position of the parts.

40 Fig. 9 is a fragmentary perspective view of one unit of a radiator core in its completed form. Fig. 10 is a fragmentary cross section taken on line 10-10, Fig. 9 of a radiator core showing air and water passages. Figs. 11 and 12 are fragmentary vertical

longitudinal sections of the machine, on an enlarged scale, taken on line 4-4, Fig. 1, and showing the different stages of folding an integral end wall together with the fin strip between the two side walls of a radiator core unit. Figs. 13-17 are fragmentary vertical longitudinal sections of the machine, on an enlarged scale, taken on line 4-4, Fig. 1, and showing different positions of its parts during the successive stages thereof for forming the seamed or locked end wall together with the fin strip between the free ends of the two side walls of a radiator core unit. Fig. 18 is an enlarged fragmentary section of the finished radiator 70 unit shown in Fig. 17.

Similar characters of reference indicate corresponding parts throughout the several views.

This machine is particularly designed for 75 folding or bending and seaming or locking a corrugated strip of metal so as to form two side walls 1, 2 which are connected at two of their corresponding ends by an integral end wall 3, while their opposite corresponding free ends are connected by a seamed or locked end wall 4, thereby forming a unit of a radiator core, as shown in Fig. 9. The outer walls of each unit are provided with offset portions 5, so that when 80 the several units comprising the radiator core are assembled water passages 6 are formed between the opposing outer walls of said units, as shown in Fig. 10. Arranged in the space between the opposing inner 85 walls of each unit, is a corrugated radiating web, strip or fin 7 which divides said space into a plurality of air conducting passages 8. The integral end wall 3 of this strip is formed by bending that part of the metal 90 strip at its turn so that the same is folded twice upon itself into substantially the shape of the letter Z and comprises an outer transverse fold or plait 9 having a groove or opening between its walls and a corresponding inner fold or plait 10 which is pressed tightly together. The adjacent end of the fin or web 7 is bent upon itself to form a transverse fold or plait 11 which embraces the inner fold 10 of the strip, with its free 95 end 12 interlocked in the opening between the walls of the outer fold 9. The seamed or interlocked end wall 4 at the opposite free ends of the side walls of this strip is composed of a female member which com- 100

105

110

prises an outer transverse fold or plait 13 having a groove or opening between its walls and an inner fold or plait 14 having a groove or opening between its walls, said female 5 member comprising one of the free ends of said strip, while the corresponding free end of the other wall of the strip comprises the male member. This male member is composed of a closed fold 15 which interlocks 10 with the opening formed between the inner fold or plait 14, while the corresponding free end of the fin strip 7 is composed of a free end 16, which embraces the outer side of a fold 17, which interlocked in the opening 18 between the walls of the outer fold 13 of said female member. The several folds or plaits formed at both ends of each radiator core unit are pressed tightly together, as 15 20 hereinafter described, so as to seal the same against leakage. The end wall 4 is preferably soldered after the pressing operation, while it is unnecessary to solder the integral end wall 3.

25 The machine for performing the functions above mentioned comprises a main frame for supporting the working parts thereof, which consists of a horizontal table 18 adapted to be supported by legs 19. Projecting horizontally and forwardly from the front end of this table is a shelf 20 upon which the strip to be operated on is supported. This strip is guided between two longitudinal guide bars 21 arranged on the 30 upper side of the shelf.

22 represents a fixed jaw or die which is rigidly secured to the upper side of the table and in alignment with the guideway of the shelf 20. Pivoted in rear of this die is a 35 vertically movable holding jaw or die 23 provided on its upper side with a suitable handle 24. The opposing faces of these jaws are fluted or corrugated to correspond to the contour of the strips of metal, so as to permit the same to be held firmly in place during operation thereon.

For retaining the lower wall of the metal strip against the fixed jaw 22, two sections 25, 25 of a lower mandrel are provided which 40 are movable horizontally and transversely toward and from each other. These lower mandrel sections are guided in suitable ways 26 which are arranged on the upper side of the table on opposite sides of the fixed jaw, 45 so that said sections may be moved toward each other over the latter and retracted so as to clear the upper surface of the fixed jaw. Surmounting the lower mandrel sections 25 are two corresponding sections 27, 27 of an 50 upper mandrel which travel over said lower sections and are guided in the ways 26. These sections are also adapted to move horizontally toward and from each other so as to hold the fin strip which during the operation of the machine, rests on the upper side

of the lower mandrel sections, as shown in Figs. 11-17. The upper and lower sides of both sets of mandrel sections are corrugated to correspond to the radiator forming strips.

Both sets of mandrel sections may be 55 moved toward and from each other into and out of their operative position by any suitable means, this being accomplished in a satisfactory manner by the means which are shown in the drawings and which comprise 60 two elbow levers 28 pivoted to swing vertically on the main frame below the table. The upper arm of each lever projects through a slot 29 in the table, through a slot 30 in the outer part of the corresponding lower mandrel section 25 and into an opening 31 in the outer part of the corresponding upper mandrel section 27. The elbow levers are oscillated by means of a treadle 32 pivoted on the frame below the table and connected by 65 means of link rods 33 with the lower arms of said levers, a spring 34 connecting the treadle with the adjacent fixed part of the frame to retain the parts in their normal or inoperative position. Inasmuch as the upper arm of the elbow lever engages an elongated slot in the corresponding lower mandrel section it can readily be seen that although the latter may be moved inward by the action of the elbow lever, as shown in 70 Fig. 8, it cannot be moved outward to the position shown by dotted lines in said figure. The preferred means for causing said section to move outwardly with the elbow lever upon releasing the treadle, is constructed as 75 follows:

Arranged adjacent to the inner edge of the slot 30 of each lower mandrel section is a vertical opening 35 which is adapted to receive a coupling or locking pin 36 passing 80 through an opening 37 in the corresponding upper mandrel section when the said sections are in their operative position, shown in Fig. 8. This pin is moved to engage with the opening 35 by means of projections 38 secured to opposite sides of the hinge die and adapted to engage the heads of the pins 36 when the hinge die is swung to the horizontal position shown in said figure. Upon the outward mutual movement of the mandrel sections, each of the pins 36 engages an inclined plate or uncoupling wedge 39 extending across the top of the guideway 26 and provided with a slot 40 which receives the shank of said pin. As the pin engages 85 this slot the underside of the head of said pin engages the inclined upper surface of the wedge and withdraws the pin from engagement with the corresponding lower mandrel section, so that when the treadle is again 90 depressed, the levers 28 will cause the two sets of die sections to move inwardly and hold the respective metal strips in position.

In the operation of this machine so far as the fixed jaw, hinge jaw, and mandrel sec- 95

tions are concerned, the operator first places the corrugated strip of metal on the fixed jaw with a part, preferably half thereof, projecting beyond the inner or rear end of said fixed jaw. The lower mandrel sections which at this time are in their outermost position, are now moved inwardly over the fixed or lower jaw or die and that part of the strip resting thereon so that the corrugated underside of these sections fit the upper side of the strip and thereby retain the same in position. The upper mandrel sections having been moved inwardly in unison with the lower sections are now allowed to move outward again by the releasing of the treadle by the operator, leaving the lower sections still in their inner position. The corrugated web or fin strip is then placed on the upper side of the two lower mandrels with a small fraction thereof projecting over the rear edge of said mandrels. Now the upper mandrels are moved inwardly over the lower mandrels and that part of the strip resting thereon so as to retain the same in position. While the parts remain in this position, the other section or half of the corrugated strip, which forms the other side wall of the radiator core unit, is folded or bent forwardly by means of the hinge jaw being swung forwardly and downwardly, thereby placing the strip with its corrugations engaging the corresponding corrugations on the upper side of the upper mandrel sections and retaining the same between the latter and said hinge jaw. At this time a portion of the sheet of metal at the fold of this strip projects beyond the rear edges of the mandrel sections, as shown in Fig. 11. While in this position this projecting portion is folded, plaited or doubled upon itself by means which are preferably constructed as follows: 41 represents a transverse folding blade which is adapted to be moved vertically immediately in rear of the hinge jaw and mandrel sections and toward and from the lower fixed jaw for the purpose of causing the lower edge of this blade to engage that portion of the metal strip and fin which projects beyond the rear ends of these sections and bending the same downwardly into preferably doubled form. This folding blade is mounted on a vertically swinging handle or lever 42, which is pivoted to a lug 43 arranged on the upper side of the table and to one side of the jaws and mandrel sections.

A vertically movable bending die or bar 44 is arranged immediately in rear of the fixed jaw, which is adapted to bend that portion of the metal strip and fin projecting beyond the rear edge of the folding blade when in its lowered position. The upper portion of this die is rounded, as shown, so as to act upon the metal gradually or uniformly without injuring or cutting the metal strip. This die may be guided in any well known manner, and the vertical movement of the same, which takes place during the bending operation, is effected by means of lifting wedges 45 arranged to travel back and forth over the table and underneath the lower edge of the bending die. In its lowermost or inoperative position, the bending die rests upon the table and at that time the lifting wedges are arranged in rear and out of engagement with said die. Upon moving these wedges forwardly the same engage the notches 46 in the underside of the bending die and raise the same to the bending or operative position. To permit the forward movement of the wedges in raising the bending die, the lower fixed jaw is provided in its underside with recesses 47. At their rear ends these wedges are secured to the lower front part of a horizontally and longitudinally movable presser bar or slide 48 which is guided on the table between guides 49. The forward movement of this slide together with the lifting wedges 45 is produced by springs 50 interposed between the rear end of the slide and a bracket 51 secured to the table. The rearward movement of this slide and the parts connected therewith is produced by means of a horizontally swinging elbow lever 52 pivoted to the top of the supporting table adjacent to the folding blade lever and having an inner arm which is connected with the upper side of the slide by a pin 53 secured to said slide and passing through a slot 54 in the adjacent arm of the elbow lever, while the outer arm is adapted to be engaged by a tail 55 secured to the lower portion of the folding blade lever below the fulcrum thereof. During the upward movement of the blade lever its tail 55 engages the outer arm of the elbow lever 52 and turns the same in a direction which will cause the inner arm thereof to move the slide rearwardly to the position shown in Fig. 1. The engagement of this tail with the adjacent arm of the elbow lever also serves as a stop to limit the lateral movement of the blade lever and hold the same in a substantially upright position. After the slide reaches its outermost position it is automatically locked against forward movement by means of a latch or locking lever 56 pivoted on the adjacent part of the table so as to swing vertically and having an inner arm which is provided with a locking nose 57 adapted to engage a recess or opening 58 in the upper adjacent part of the slide and an outer arm which projects horizontally into the path of a tappet arm 59 pivoted to a bracket 60 secured to the table or other adjacent part of the frame. The nose 57 of this locking lever is held constantly in the recess 58 by means of a spring 61 arranged between the underside of its outer arm and the top of 130

the table, as shown in Fig. 3. In order to release this nose from engagement with the presser bar or slide 48, the folding blade handle is provided with a releasing lever 62 preferably constructed in the form of a spring and secured thereto at its lower end by means of a bolt 63 while its outer end is free and is provided with a releasing pin 64 which is adapted to pass through an opening in the adjacent part of the blade lever or handle and engage the underside of the inner arm of the tappet 59. In its normal position, the releasing pin 64 is held out of the path of the tappet arm by the releasing lever 62 which is normally held in the position shown in Fig. 7. When it is desired to cause the slide to move outward or toward the jaws and mandrels, the folding lever is swung to the horizontal position in the act of folding a strip of metal, at which time the pin 64 is below the path of the inner arm of the tappet bar, and then the spring lever 62 is pressed inwardly against the face of the folding lever thereby moving the releasing pin inwardly into the path of the tappet arm. Upon now moving the blade lever upwardly, the tappet arm will be turned vertically by the action of the releasing pin engaging the underside of the inner arm of said tappet, while the outer arm thereof will be moved downwardly striking the corresponding outer arm of the locking lever 56, thereby releasing the inner arm thereof from the slide and permitting the latter to move forwardly under the action of its propelling springs. The outer arm of this locking lever is provided with a suitable handle 65 for manually operating the same.

In order to limit the rearward movement of the hinge jaw and to support the same when it is not in use and in its inoperative position, a stop is provided which is formed by notching the upper parts of the guide bars 49 so as to form a stop face 66 against which the rear part of said hinge die is adapted to rest.

In forming the two end walls of a radiator core unit by the operation of this machine the integral end wall 3 is first made and after that is completed the interlocked end wall 4 is made.

Passing now to the operation of this machine by making the integral end wall first, a previously corrugated and off-set strip of metal, having a length somewhat greater than the combined length of two finished side walls of a radiator core unit so as to allow for the making of the end walls thereof, is first placed lengthwise upon the guide shelf and over the opposing faces of the fixed and hinge jaws so that part of this strip adjacent to the center thereof is arranged between the rear ends of said jaws and spans the space between the same. At this time

the parts of the machine are in the position shown in Figs. 1, 2, 3 and 6 except that instead of the lower mandrel sections being in the position shown in Figs. 1 and 2, they are withdrawn to the position which the upper mandrels assume in said figures so as to make a clear path for placing the corrugated strip upon the fixed jaw. The operator now presses the treadle so as to move the two upper and lower mandrel sections inwardly over the strip resting on the fixed jaw, after which he releases his foot from the treadle to bring the two upper mandrel sections to their outermost position, as shown in Figs. 1 and 2. The lower sections, however, remain in their inward position, due to the fact that the upper arms of the elbow levers pass idly through the elongated slots therein during the outward movement of said levers. The web or fin strip, which divides each radiator core unit into two rows of conducting air passages, is now placed upon the upper side of the contracted lower mandrel sections and arranged vertically in line with the lower strip with a portion thereof projecting beyond the rear edge of the fixed jaw and mandrel sections to allow for the fold or plait, as shown clearly in Fig. 11. The upper mandrel sections are now drawn together by pressing down the treadle to hold the fin strip firmly in place. The extended portion of the lower strip of metal is then brought forwardly over the corrugations of the upper mandrel sections by swinging the hinge jaw forwardly and downwardly, thereby bringing with it said portion of the strip and holding it firmly in place between the opposing faces of said jaw and mandrel sections, as shown in Fig. 11. Upon the downward movement of the hinge jaw, the projections thereon engage the retaining pins 36 in the upper mandrel sections and force them through the corresponding openings in the lower sections, so that when the operator subsequently releases the treadle as hereinafter described, both mandrel sections will be moved outwardly in unison. The two walls of the core unit together with the fin strip are then bent downwardly by the folding blade along the rear edges of the mandrel sections. The operator then allows the tappet to release the locking lever from engagement with the spring pressed slide or presser bar, whereby the latter instantaneously moves forward, raises the bending die so as to turn the rear-most portion of the integral fold of the strip upwardly along the rear side of the folding blade, and immediately thereafter the front portion of the presser bar strikes a hard blow against the rear side of the bending die so as to flatten and compress the folded or plaited portions of the integral end wall and fin strip, as shown in Fig. 12. If desired the integral wall may be compressed

tightly together by removing the folding blade from the inner loop formed in said wall and allowing the presser bar to strike another blow against the bending die, the 5 result of which is shown to the right of Figs. 13-17 and also in Fig. 9.

After thus forming the integral end wall and interlocking the adjacent end of the fin strip therewith, the several strips forming 10 the core unit are removed from the machine by first raising the hinged upper jaw, and then withdrawing both sets of mandrel sections.

In forming the opposite end wall of the 15 radiator core unit, the side walls and fin strip are reversed end for end and placed on the guide shelf with that side wall of the strip having the greater length resting on the lower fixed jaw so that a portion of its free 20 end projects rearwardly over the bending die and the adjacent part of the face of the hinge jaw. The operator then depresses the treadle which causes both sets of mandrel sections to move inwardly, the lower sections 25 passing over the side wall of the strip resting on the fixed jaw to hold the same in place. The upper mandrel sections are moved outward and the fin strip placed on the upper side of the lower mandrels with a 30 portion thereof projecting rearwardly over the rear edge of said lower mandrels, after which the upper mandrel sections are again moved inward and the hinge jaw is swung downwardly upon the upper mandrel sections, 35 whereby the rearwardly projecting end portion of the lower side wall is bent forwardly and clamped between the upper side of the upper mandrel sections and hinge jaw and the turned portion thereof left in a position in 40 which the same projects over the upper end of the bending die, as shown in Fig. 13. The folding blade is now pressed downwardly so as to form a plait or downward doubled bend in the projecting portions of the lower 45 wall and fin strip, which in effect produces an upwardly opening transverse groove, as shown in Fig. 14. The folding blade is now raised, after which the hinge die is swung rearwardly and the free end of the other 50 side wall of the radiator core unit is placed upon the upper side of the upper mandrel sections with a portion thereof projecting rearwardly over the rear edge of the mandrel sections and overlapping the doubled end 55 portion of the lower wall and fin strip. The hinge die is then swung downwardly over the upper wall of the strip, as shown in Fig. 15. While the parts are in this position, the folding blade is pressed downwardly to 60 form a fold or plait in the upper wall of the strip similar to that formed in the lower wall and fin strip produced in the step heretofore described. The fold in the upper wall of the strip seats itself in the transverse opening formed by the last described opera- 65

tion. After the blade is fully depressed, the locking lever is tripped and the presser bar allowed to move forward so as to compress the folds, as shown in Fig. 16. The folding blade is now raised and the presser bar 70 moved rearwardly by the action of the elbow lever being swung outwardly by means of the tail of said folding blade engaging the adjacent arm of the elbow lever. The presser bar is again caused to strike a blow 75 against the folded or plaited end portion of the core unit and compress all folds tightly together, as shown in Fig. 17. The completed core unit may now be removed by raising the hinge die and withdrawing both 80 sets of mandrel sections by releasing the foot treadle.

By thus forming the end walls of a core unit, the end walls are not only sealed, but the fin strip is firmly interlocked therewith 85 and prevented from displacement therefrom. A plurality of such units are then assembled so as to form water tubes between the opposing walls of the adjacent units, as shown in Fig. 10. The several units are then dipped 90 at the front and rear ends into a solder bath for uniting the same, and a coating of solder is also applied to the interlocked end walls of the units so as to exclude water from the corresponding air passages, thereby completing 95 the core of the radiator. Thereafter, this core is assembled in the ordinary way with the upper and lower headers or water boxes and inclosed in a frame.

My improved machine for bending, folding and seaming a strip of metal to form the end walls of a radiator core unit, together with uniting the fin strip therewith for dividing the unit into a plurality of rows of air conducting passages, permits of accomplishing this work easily, effectively and in a comparatively short time.

I claim as my invention:

1. A metal bending machine comprising a lower jaw, an upper jaw, said jaws being 110 movable relatively to each other, and mandrels arranged one above the other and each comprising two sections which are movable laterally into and out of the space between said jaws.

2. A metal bending machine comprising a lower fixed jaw, a vertically swinging upper jaw movable toward and from the fixed jaw and adapted to bend a strip of metal between them, upper and lower mandrels adapted to 120 move simultaneously into the space between said jaws for supporting strips of metal, and means for withdrawing said upper mandrel independent of said lower mandrel comprising an elbow lever connected with said upper mandrel, and foot operated means for turning said lever for removing said mandrel from the space between said jaws.

3. A metal bending machine comprising a lower fixed jaw, a vertically swinging up- 130

- 6 per jaw movable toward and from the fixed jaw and adapted to bend a strip of metal between them, upper and lower corrugated mandrels adapted to move simultaneously 5 into the space between said jaws, and means for causing said mandrels to move in unison out of the space between said jaws, said jaws and mandrels being adapted to finally co-operate at the same time.
- 10 4. A metal bending machine comprising a lower fixed jaw, a vertically swinging upper jaw movable toward and from the fixed jaw and adapted to bend a strip of metal between them, upper and lower mandrels 15 adapted to move simultaneously into the space between said jaws, means arranged on said upper mandrel and adapted to co-operate with said lower mandrel while in their innermost position for temporarily connecting said mandrels so that they will move together from the space between said jaws, and means to cause said mandrels to move from said space.
- 15 5. A metal bending machine comprising a lower fixed jaw, a vertically swinging upper jaw movable toward and from the fixed jaw and adapted to bend a strip of metal between them, upper and lower mandrels adapted to support strips of metal and each comprising 20 two sections movable laterally into and out of the space between said jaws from opposite sides thereof, means for operating the upper mandrel sections independent of the lower mandrel sections while the latter are 25 in their innermost position, and means for removably connecting said upper and lower mandrels while in their operative position to cause the withdrawal of the lower mandrel sections in unison with the upper mandrel sections.
- 30 40 6. A metal bending machine comprising a lower fixed jaw, a vertically swinging upper jaw movable toward and from the fixed jaw, upper and lower mandrels movable into 45 and out of the space between said jaws, means for moving said mandrels simultaneously into the space between said jaws but movable independently therefrom comprising an elbow lever engaging with an 50 opening in said upper mandrel and projecting through a slot in said lower mandrel.
- 55 7. A metal bending machine comprising a lower fixed jaw, a vertically swinging upper jaw movable toward and from the fixed 60 jaw, upper and lower mandrels movable into and out of the space between said jaws and each comprising two sections, means for moving said mandrels simultaneously into the space between said jaws but movable independently therefrom comprising elbow levers engaging openings in said upper mandrel sections and projecting through slots in said lower mandrel sections, and means for connecting the upper and lower mandrel sections while in their inward position
- 65 to cause the withdrawal of the lower mandrel sections in unison with the upper mandrel sections and for disconnecting the same in their outward position to permit independent inward movement of the same. 70
8. A metal bending machine comprising a lower fixed jaw, a vertically swinging upper jaw movable toward and from the fixed jaw and adapted to bend a strip of metal between them, upper and lower mandrels 75 adapted to support strips of metal and each comprising two sections movable laterally into and out of the space between said jaws from opposite sides thereof, means for operating said upper mandrel sections independent of the lower mandrel sections while the latter are in their innermost position and means for connecting said upper and lower mandrels while in their operative position to cause the withdrawal of the lower mandrel sections in unison with the upper mandrel sections comprising a locking pin slidably arranged in each of the upper mandrel sections and adapted to engage with an opening in the companion lower mandrel 80 section, and means arranged on said upper jaw for shifting said locking pins into engagement with said openings when said movable jaw is swung to its operative position. 85
9. A metal bending machine comprising a lower fixed jaw, a vertically swinging upper jaw movable toward and from the fixed jaw and adapted to bend a strip of metal between them, upper and lower mandrels 90 adapted to support strips of metal and each comprising two sections movable laterally into and out of the space between said jaws from opposite sides thereof, guides for said mandrels, the upper mandrel sections being 95 operable independently of the lower mandrel sections while the latter are in their innermost position, means for causing the withdrawal of the lower mandrel sections in unison with the upper mandrel sections comprising a locking pin slidably arranged in each of the upper mandrel sections and adapted to engage with an opening in the companion lower mandrel section, projections on said upper jaw for moving said locking pins into engagement with said 100 openings when said upper jaw is swung into a horizontal position, and wedges for releasing said pins from the openings in said lower mandrel sections when the latter are 105 withdrawn from the space between said jaws. 110
10. A metal bending machine comprising a lower fixed jaw, a vertically swinging upper jaw movable toward and from the fixed 115 jaw and adapted to bend a corrugated strip of metal between them, upper and lower mandrels movable into and out of the space between said jaws and adapted to support strips of metal between their opposing 120 jaws. 125
- 130

- faces, a folding blade movable vertically in rear of said mandrels and jaws and adapted to form a plait in said strips of metal, a bending die in rear of said fixed jaw, a presser bar, a latch for holding said bar in its rearward position, a vertically swinging lever on which said folding blade is mounted, and means on said lever for releasing said latch from said bar.
- 10 11. A metal bending machine comprising a lower fixed jaw, a vertically swinging upper jaw movable toward and from the fixed jaw and adapted to bend a corrugated strip of metal between them, upper and lower mandrels movable into and out of the space
- 5 between said jaws and adapted to support corrugated strips of metal between their opposing faces, a folding blade movable vertically in rear of said mandrels and jaws and adapted to form a plait in said strips of 20 metal, a bending die in rear of said fixed jaw, a presser bar, a latch for holding said bar in its rearward position, a vertically swinging folding lever on which said folding blade is mounted, a tappet arm, and a 25 releasing lever arranged on said folding lever and provided with a pin adapted to removably engage said tappet for releasing said latch from said presser bar.
